UNITED STATES PATENT OFFICE.

GEORGE JOHN STEVENS, OF LONDON, ENGLAND, ASSIGNOR, BY MESNE ASSIGNMENTS, TO AMERICAN ATTACHMENT COMPANY, OF PORTLAND, MAINE, A CORPORATION OF MAINE.

GUIDE FOR SEWING-MACHINE ATTACHMENTS.

No. 829,126.

Specification of Letters Patent.

Patented Aug. 21, 1906.

Application filed December 12, 1902. Serial No. 134,979.

To all whom it may concern:

Be it known that I, GEORGE JOHN STEVENS, of London, England, but now temporarily residing in the city, county, and State of New York, have invented a certain new and useful Improvement in Guides for Sewing-Machine Attachments; and I do hereby declare the following to be a full, clear, and exact specification of the same.

10 The object of my invention is to construct a simple, inexpensive, and efficient guide for sewing-machine attachments, and more particularly that class of such attachments as are adapted to blindstitch or fell, serge or overcast, and overseam; to make such a guide readily adjustable, so that cloths of varying thicknesses may be readily stitched, and to guide both the fold of the cloth and the lower single layer of cloth when blind-
20 stitching or felling. I accomplish this object by the construction, arrangement, and operation of parts hereinafter described, the particular features of novelty which constitute my invention being pointed out in the claim
25 at the end of this specification.

In the drawings which form a part of this specification, and in which similar letters of reference refer to similar parts wherever they occur, Figure 1 is a side elevation showing a 30 blindstitching attachment with my improved guide applied thereto in position on the head of a sewing-machine. Fig. 2 is a front elevational view of the parts shown in Fig. 1. In this view I show a piece of cloth properly 35 folded under the presser-foot and guided to the needle to be stitched. Fig. 3 is a plan view showing a portion of the top plate of an attachment with my guide in place thereon. Fig. 4 is a side elevation of the parts shown in Fig. 3. Fig. 5 is a side elevation of the guide 40 by itself looking at the inner side of the same, and Fig. 6 is a plan view of a plain presser-foot adapted for use with the guide.

My improved guide is especially adapted 45 for use with a blindstitching attachment such as is shown in my application, Serial No. 77,088, in which a pusher pushes the cloth away from the needle at every alternate stitch, producing a zigzag row of stitching, and in the use of which it is desirable to so 50 guide the cloth to the needle that the needle will be prevented from passing entirely through the fold of the cloth from side to

side, but will enter and pass out of the cloth on the same side thereof, producing a true 55 blindstitching, as is fully described in the said application.

To the front edge of the attachment A—i.e., the side nearest to the operator—I secure a plate B. This plate B is provided with two 60 slots b b' and is held against the side of the attachment A by two screws b^2 b^3 , which pass through the slots b b' and engage in screw-threaded holes in the side of the attachment A, the said plate B being free to move transversely along the edge of the attachment A, being held against displacement by the heads of the screws b^2 b^3 . The plate B is also formed with two upwardly-extending lugs B' B^2 . A screw C, having a milled head, 70 passes through the lug B' and engages with the head d of the guide D, which is provided with a screw-threaded aperture for the purpose. The guide D consists of the plate having the head d at one end and a downwardly-extending flange d^2 at the other end, the flange d^2 being so constructed and arranged 75 that it passes down by the side of the attachment A next to the needle E and extends from a point nearly in line with the pusher A' 80 to a short distance beyond the front side of the attachment A. By turning the screw C by its milled head the guide-plate and its flange d^2 may be moved upwardly and downwardly away from or toward the base-plate 85 of the sewing-machine.

To the end of the attachment A opposite the needle E, I secure an upwardly-extending plate F, the upper portion of which is bifurcated, forming jaws f f' . The lug B^2 of the 90 plate B is provided with a block B^3 , having a central screw-threaded aperture b^4 . An adjusting-screw G, provided with a milled head and having a circumferential groove or channel g in its head, passes between the jaws f f' 95 of the plate F, the jaws f f' having a bearing in the groove or channel g and engages in the screw-threaded aperture b^4 . As this adjusting-screw G is held by the jaws f f' and is turned the one way or the other by its milled 100 head it carries the block B^3 , and consequently the plate B, and the guide D and its flange d^2 toward or away from the needle E, and in this manner adjustment may be made 105 for sewing any thickness of material.

Instead of the presser-foot ordinarily used

for the machine for plain sewing I employ a presser-foot such as shown in Fig. 6, having a recess X in its side next and opposite the needle E in order to receive the bulge of the cloth when the pusher A' is extended and pushes the edge of the cloth away from the needle.

In carrying my invention into operation the attachment is secured to the work-plate 10 of the machine in the usual manner by a set-screw. The cloth to be stitched is then folded as shown in Figs. 1 and 2—that is to say, a hem is first turned up and then the body of the cloth is carried back over the hem, leaving 15 the single layer of the cloth under the fold and projecting slightly beyond the fold. The cloth thus folded is inserted under the presser-foot H with the fold against the side of the flange d² of the guide D and the single 20 layer under the said flange d², which may be slightly raised from the work-plate of the machine for this purpose by turning the screw C. The position of the flange d² with respect to the needle E is determined by the 25 thickness of the material to be stitched, it being necessary to so guide the cloth to the needle that the latter cannot pass entirely through the cloth in the fold from side to side, but will enter and pass out of the same

side, splitting or passing approximately 30 through the middle of the material forming the said fold. As hereinafter stated, my improved guide may be adjusted as desired with relation to the needle and to the presser-foot by simply turning the adjusting-screw G the 35 one way or the other, so that the materials of any thickness and almost of any degree of thinness may be blindstitched.

Having now described my invention, what I claim as new, and desire to secure by Letters Patent, is—

In combination a base-plate, a horizontally-adjustable plate held against one edge of the base-plate, a plate F extending up from another edge of the base-plate, a screw 45 held by the upwardly-extending plate and engaging the adjustable plate, a guide pivotally secured to the adjustable plate and having its guiding-face extending down in front of the base-plate and means for adjustably 50 holding the guide, substantially as described.

In witness whereof I have hereunto set my hand in presence of two witnesses.

GEORGE JOHN STEVENS.
